UNITED STATES PATENT OFFICE.

PAUL S. MILLICE AND MARTIN MUELLER, OF HAMILTON, OHIO, ASSIGNEES TO
HERRING-HALL-MARVIN SAFE COMPANY, OF NEW YORK, N. Y., A CORPORATION
OF NEW YORK.

SHEET-METAL SAFE.

1,150,613.

Specification of Letters Patent.

Patented Aug. 17, 1915.

Application filed January 14, 1915. Serial No. 2,117.

To all whom it may concern:

Be it known that we, PAUL S. MILLICE and MARTIN MUELLER, both citizens of the United States, residing in Hamilton, in the county 5 of Butler and State of Ohio, have invented certain new and useful Improvements in Sheet-Metal Safes, of which the following is a specification, reference being made to the accompanying drawings, forming a part 10 thereof.

Our invention relates to that species of safes and cabinets formed of sheet metal, preferably of high tensile steel, the members comprising our safe construction being assembled and joined together so as to form 15 a double walled structure, which may be used in various relations, though particularly available for fire-proof safes and the like. Such fire proof safes have hitherto, 20 for the most part, been made of cast iron frames with flat plates riveted thereto, the intervening spaces being filled with a hydraulic cement compound.

The objects of our invention, among other 25 things, are to provide a sheet-metal safe which shall be simple and economical in its formation and structure, and easily assembled; also to so form the body structure that an extremely rigid sheet-metal wall construction is obtained with a minimum number 30 of welded joints, doing away entirely with rivets to form a union of the parts or members comprising the outer shell structure; also to provide an improved safe construction of sheet-metal in which the passage 35 of heat or flame through either the wall structure itself, or the door joints is fully and effectively prevented when the safe is subjected to fire or heat.

40 A further advantage of our invention is the construction of sheet-metal safes which shall have the massive appearance desirable in articles of this character, yet embodying a comparatively light structure, the parts 45 comprising which will have a certain degree of elasticity and expansion under the action of heat. This feature of construction effectively prevents the safes from being broken or cracked in case of the falling of the safe, 50 for example in the collapse, through fire, of the floor upon which the safe is located, or should a heavy body fall upon the safe through the floor above.

Further objects relating to the construc-

tion and formation will more fully and definitely appear in this specification. 55

We accomplish the objects of our invention by a structure illustrated in the accompanying drawings.

Referring now to the drawings, Figure 1 60 is a front view; Fig. 2 is a top plan view; Fig. 3 is an enlarged vertical section on the line 3—3 of Fig. 2 looking in the direction of the arrow; Fig. 4 is a detail view of plate 38 shown in Fig. 3; Fig. 5 is a sectional view 65 taken on the line 5—5 of Fig. 3 looking in the direction of the arrow; Fig. 6 is an enlarged perspective detailed view taken on the line 6—6 shown in Fig. 5 looking in the direction of the arrow; Fig. 7 is an enlarged 70 perspective view looking in the direction of the arrow shown in Fig. 8; Fig. 8 is an enlarged vertical sectional view taken on the line 8—8 of Fig. 1 looking in the direction of the arrow; and Fig. 9 is an enlarged horizontal sectional view taken on the line 9—9 75 of Fig. 1 looking in the direction of the arrow.

As herein illustrated, our improved sheet-metal safe, or cabinet, comprises a top 1 80 (Figs. 2 and 8), a bottom 2 (Figs. 3, 5, 6, and 9), sides 3 (Figs. 3, 5, 6, 8, and 9), back 4 (Figs. 3, 5, 6), and front 5, consisting of the members 5^a and 5^b (Figs. 1, 8, and 9), having a door 6 (Figs. 1, 8, and 9) hinged 85 thereto as at 7.

One of the features of our invention is the manner of connecting the forming plates and corner members, of which the safe or cabinet is constructed, without the use of 90 rivets, bolts, etc. The manner of connecting these component members permits them to warp or buckle under the action of a high degree of heat without opening any seams through which flames or hot gases can enter. 95 The connections between the plates constitute a slip joint, as distinguished from a non-yieldable connection effected by the use of rivets which are apt to be sheared by the force of expansion under the action of heat. 100

The top 1 of the safe (Figs. 2, 3, and 8) consists of a plate 9 turned over along its side edges at 10 to form grooves arranged to engage similar grooves 11 formed along the adjacent edges of corner members 12 and 13 of angular formation, the corner members 12 and 13 being located at the sides of the safe and at the upper ends thereof. The 105

front and rear edges of said top plate 9 are also turned over to form grooves 14 and 15 (Fig. 8) arranged to engage similar grooves 15^a and 16 formed along the adjacent edges 5 of the horizontally disposed flanges 17 and 18 of the back member 4, and the front member 5^a respectively, the flange 17 of the back member 4 being located at the upper end thereof, the flange 18 being carried by the 10 upper front member 5^a. The front members 5^a 5^b are welded together at 19 to form a substantially one piece front. Each front member 5^a is provided with an inwardly directed flange provided with a groove 16 15 along its edge, one only being shown.

The top and bottom front members 5^a are further provided with an inwardly extending flange 20 (see Figs. 7 and 8, one only being shown) formed to provide door jamb members 21, 22, and a top 23 of an intermediate inner compartment 24; the top 23 of said inner compartment 24 is provided with an upstanding flange 25, to be hereinafter referred to.

25 The flanges 18, 23 and 25, and the remaining member 26, of the top front member 5^a are struck out of one piece of sheet-metal. The side members 5^b of the front (one only being shown in Fig. 9) are formed in a similar manner, that is to say, they consist of the exterior flange 27 and inwardly directed flange 28 having the jamb portion 29 and side member 30 for the intermediate interior chamber 24, the side member 30 being provided with a flange 31 to coöperate with the flange 25 of the front members 5^a for connection with the side partition walls 32 (one only being shown in Fig. 9), and the upper and lower walls 33 (one only being shown in Fig. 8) for a central inner compartment 34. The flanges 28 and 27 are integral with the member 35 of the front members 5^b. The exterior flange 27 carries a turned-up edge 36 to provide a groove 37.

40 The sides 3 of the safe or cabinet consist of plates 38 (see Figs. 3, 4 and 9) having the ends thereof turned-up at 39 and 40 (Fig. 9) to form grooves. The turned-up edge 40 of each plate 38 engages the grooves 50 37 in the front members 5^b. The turned-up edge 39 of said plates engages the groove 41 provided by turning over the adjacent edge 42 of the flanges 43 of the back member 4. The back member 4 consists of a plate 44 having the flanges 17 top and bottom (Fig. 8) and flanges 43 at the sides thereof. (Fig. 9).

45 It will be seen that the top 1 of the safe is formed by the plate 9 which is interlocked with the flange 17 of the back 4, the flange 18 of the top front member 5^a and flanges 11 of the side corner members 12 and 13. The bottom 2 of the safe is formed in a similar manner, and consists of a plate 45 (Fig. 5) which engages the turned over edge 45^a

of the flange 46 carried by the back 4, and a flange, similar to the flange 18, on the front, bottom member 5^b.

The back 4 consists of the plate member 44 having the top flange 17, the side flanges 43, and the bottom flange 46 are each provided with a turned over edge to form a groove adapted to interlock with plates to complete the top 1 and bottom 2. The front 5 is made up of the members 5^a, 5^a, 5^b, 5^b 75 each provided with an exterior flange having a turned up edge to provide a groove to receive the adjacent turned-up edges of the top and bottom plates 9 and 45 respectively (as shown in Fig. 8).

The turned over edges 47 of the bottom plate 45 (Fig. 5) interlocks with the turned-up edges 48 of the horizontal members 49 of the side corner members 50 (Fig. 3).

The sides 3 of our improved safe are provided with turned over ends, top and bottom, indicated by 51 and 52 in Fig. 3, which engage, or interlock, with grooves 53 and 54 respectively formed by the turned over ends 55 and 56 of the vertical members 57 90 and 58 of the corner members 13 and 50, both side plates being alike. To form a rear interior chamber 59, we provide a partition wall 60.

The door 6 comprises top and bottom 95 jamb members 61, the top member only being shown in Fig. 8; and side jamb members 62, one only being shown in Fig. 9; a front plate 63 and back plate 64.

The front plate 63 is provided with an 100 inwardly turned flange 64^a, turned over at its end 65 to provide a projection to enter a pocket 66 formed by a plate 67 secured to the flange 20 having its end turned over as at 68.

The side jamb member 62 carries a projecting portion 68 struck up therefrom to enter a pocket 69, struck up from the material of the jamb member or flange 20 of the front members 5^a.

110 The pockets 66 and 69 together with their coöperating projections 65 and 68, constitute a baffle when the door is shut to prevent the passage of flame to the interior of the safe. To still further prevent the entrance of 115 flame we provide an interior door 70 made up of the plates 71 and 72, secured together to form a hollow structure which may be lined with any fire-proof material such as asbestos. The door 70 is hinged to the members 23 of the inwardly projecting flanges of the front members 5^a, top and bottom, as at 72^a.

To secure the side plates, top plate and bottom plate to the corner members, we 125 preferably spot-weld the same as at 73.

130 It will be seen from the foregoing that the side, top and bottom of the safe are made up of a plurality of members interlocked in such manner as to provide a water-tight con-

nection, but nevertheless adapted to expand under the influence of heat. As there are no riveted or bolted joints, the sides, top, bottom, front, or back, of the safe can expand or buckle without opening any seams through which flame can pass.

Furthermore, our improved connection will not break should the safe or cabinet fall; there is nothing to strip or shear; and, to still further protect the contents, the safe may be lined with some fire-proof material such as asbestos.

The door is provided with a suitable lock, preferably a combination lock, but as this forms no part of our invention, we do not describe same in this specification.

Manifestly, there are many methods of assembling the various parts which comprise the outer shell of our improved safe construction, before the welding of the corner flanges of the front and back. We will set forth one method by way of example as follows: The body sheets, which consist of the side-plates, top, and bottom, with their respective turned-up grooved portions, forming engaging hooks, are interlocked with the turned-up grooved portions formed in the return flanges formed on the front members. We then insert and slide the corner members forward so that the turned-up grooved portions of these corner members are interlocked with their contiguous turned-up grooved parts formed on what we have just called the body sheets. When this has been completed the back is slipped over the sides, top, bottom and corner members until the turned-up grooved portions of the back pass over the grooved portions on the top, bottom and side plates, when the back is returned in an opposite direction until the grooved hooks of all the parts are engaged and interlocked, and the whole outer shell construction shall have been snugly joined and fitted together. The final step consists in suitably welding the corners of the front and back to the corner members by means of the oxy-acetylene process, or any other suitable appliance.

Having thus fully described our invention, what we claim as new and desire to secure by Letters Patent is:

1. In a sheet-metal safe, the combination of rectangular top, bottom and side members each having interlocking grooved hooks along their respective engaging edges, a rectangular front member having right-angled return flanges provided with interiorly disposed grooved hooks along their parallel edges interlocked with the contiguous grooved hooks of said top, bottom and side members, a rectangular back member having right-angled return flanges provided with interiorly disposed grooved hooks along their parallel edges interlocked with the contiguous grooved hooks of said top, bottom and side members, right-angled corner members having interiorly disposed grooved hooks along their longitudinal edges interlocked with the contiguous grooved hooks of the top, bottom and side members, and means for rigidly securing the ends of said corner members to the corners of the front and back members whereby all the component members of the safe are held together.

bottom and side members, right-angled corner members having interiorly disposed grooved hooks along their longitudinal edges interlocked with the contiguous grooved hooks of the top, bottom and side members, and means for rigidly securing the ends of said corner members to the corners of the front and back members whereby all the component members of the safe are held together.

2. In a sheet-metal safe, the combination of rectangular top, bottom and side members each having interlocking grooved hooks along their respective engaging edges, a rectangular front member comprising top, bottom and side portions each having right-angled return flanges provided with interiorly disposed grooved hooks along their parallel edges interlocked with the contiguous grooved hooks of said top, bottom and side members, a rectangular back member having right-angled return flanges provided with interiorly disposed hooks along their parallel edges interlocked with the contiguous grooved hooks of said top, bottom and side members, right-angled corner members having interiorly disposed grooved hooks along their longitudinal edges interlocked with the contiguous grooved hooks of the top, bottom and side members, and means for rigidly securing the ends of said corner members to the corners of the front and back members whereby all the component parts of the safe are held together.

3. In a sheet-metal safe, the combination of rectangular top, bottom and side members each having interlocking grooved hooks along their respective engaging edges, a rectangular front member having right-angled return flanges provided with interiorly disposed grooved hooks along their parallel edges interlocked with the contiguous grooved hooks of said top, bottom and side members, a rectangular back member comprising top, bottom and side portions each having right-angled return flanges provided with interiorly disposed grooved hooks along their parallel edges interlocked with the contiguous grooved hooks of said top, bottom and side members, right-angled corner members having interiorly disposed grooved hooks along their longitudinal edges interlocked with the contiguous grooved hooks of the top, bottom and side members, and means for rigidly securing the ends of said corner members to the corners of the front and back members whereby all the component members of the safe are held together.

4. In a sheet-metal safe, the combination of rectangular top, bottom and side members each having interlocking grooved hooks along their respective engaging edges, a rectangular front member comprising top, bottom and side portions each having right-

- angled return flanges provided with interiorly disposed grooved hooks along their parallel edges interlocked with the contiguous grooved hooks of said top, bottom and 5 side members, a rectangular back member comprising top, bottom and side portions each having right-angled return flanges provided with interiorly disposed grooved hooks along their parallel edges interlocked with 10 the contiguous grooved hooks of said top, bottom and side members, right-angled corner members having interiorly disposed grooved hooks along their longitudinal edges interlocked with the contiguous grooved 15 hooks of the top, bottom and side members, and means for rigidly securing the ends of said corner members to the corners of the front and back members whereby all the component members of the safe are held together.
5. In a sheet-metal safe, the combination of a safe body having stepped top, bottom and side sheet-metal jamb members forming a door opening, each of said jamb members 25 having bent over portions integral therewith forming hollow projections with adjacent pockets therein, and a door comprising stepped sheet-metal wall members and a sheet-metal outer front plate having a return flange with bent over portions integral therewith forming hollow projections and adjacent pockets therein, adapted to cooperate with the respective pockets and projections in said door opening to constitute a 30 baffle when said door is shut.
6. In a sheet-metal safe, the combination of a safe body having stepped top, bottom and side sheet-metal jamb members forming a door opening, said top and bottom jamb 40 members having bent over portions integral therewith forming outer pockets and inner hollow projections, said side jamb members having bent over portions integral therewith forming outer hollow projections and inner 45 pockets, said pockets and projections being adjacent each other, and a door comprising stepped sheet-metal wall members and a sheet-metal outer front plate having a return flange with bent over portions integral therewith forming hollow projections and adjacent pockets therein, adapted to cooperate with the respective pockets and projections in said door opening to constitute a baffle when said door is shut.
7. In a sheet-metal safe, the combination of a safe body having stepped top, bottom and side sheet-metal jamb members forming a door opening, said jamb members having bent over portions integral therewith forming adjacent pockets and hollow projections 55 therein, and a door comprising a sheet-metal front plate having top and bottom inwardly turned flanges with bent over ends integral therewith forming hollow projections and adjacent pockets, and stepped sheet-metal wall members having integrally formed hollow projections thereby providing adjacent pockets and projections adapted to coöperate with the respective projections and pockets in said door opening to 60 constitute a baffle when said door is shut.
8. In a sheet-metal safe, the combination of a safe body having stepped top, bottom and side sheet-metal jamb members forming a door opening, said top and bottom jamb 75 members having bent over portions integral therewith forming outer pockets and inner hollow projections, said side jamb members having bent over portions integral therewith forming outer hollow projections and inner 80 pockets said projections and pockets being adjacent each other, and a door comprising a sheet-metal front plate having top and bottom inwardly-turned flanges with bent over ends integral therewith forming hollow 85 projections and adjacent pockets and stepped sheet-metal wall members having integrally formed hollow projections thereby providing adjacent pockets and projections adapted to coöperate with the respective projections and pockets in said door opening to 90 constitute a baffle when said door is shut.
